US0D1103837S

(12) **United States Design Patent** (10) Patent No.: **US D1,103,837 S**
(45) Date of Patent: ** Dec. 2, 2025

(54) **GEMSTONE**

(71) Applicant: **Albert Gad Ltd.**, New York, NY (US)

(72) Inventor: **Reuven Paikin**, Windhoek (NA)

(73) Assignee: **Albert Gad Ltd.**, New York, NY (US)

(**) Term: **15 Years**

(21) Appl. No.: **29/935,899**

(22) Filed: **Apr. 4, 2024**

Related U.S. Application Data

(62) Division of application No. 29/726,823, filed on Mar. 5, 2020, now Pat. No. Des. 1,027,715.

(57) **CLAIM**

The ornamental design for a gemstone as shown and described.

DESCRIPTION

FIG. 1 is a first perspective view of a gemstone; FIG. 2 is a second perspective view of the gemstone of FIG. 1;

FIG. 3 is a top plan view of the gemstone of FIG. 1; FIG. 4 is a bottom plan view of the gemstone of FIG. 1; and, FIG. 5 is an elevation view of the gemstone of FIG. 1, which is identical for the front, rear, left side, and right side of the gemstone.

The dash-dash broken lines depict environmental structure and form no part of the claimed design. The dash-dot-dash broken lines depict the boundary of the claimed design and form no part of the claimed design.

1 Claim, 3 Drawing Sheets
